CLAIM

I claim the ornamental design for a loudspeaker, substantially as shown and described.

DESCRIPTION

FIG. 1 is a rear perspective view of a loudspeaker showing my new design;

FIG. 2 is a top plan view thereof;

FIG. 3 is front elevational view thereof;

FIG. 4 is a left side elevational view thereof;

FIG. 5 is a right side view thereof;

FIG. 6 is a bottom plan view thereof; and,

FIG. 7 is a front perspective view thereof.
